UNITED STATES PATENT OFFICE.

CHARLES H. CROWELL, OF BROOKLYN, NEW YORK.

MULTIPLE-LENGTH SERIES-DELIVERY TAPE-MOISTENING MACHINE.

1,305,776..

Specification of Letters Patent.

Patented June 3, 1919.

Application filed February 8, 1917. Serial No. 147,324

To all whom it may concern:

Be it known that I, CHARLES H. CROWELL, a citizen of the United States, and resident of the borough of Brooklyn, county of 5 Kings, city and State of New York, have made a certain new and useful Invention Relating to Multiple-Length Series-Delivery Tape-Moistening Machines, of which the following is a specification, taken in connection with the accompanying drawing, which forms part of the same.

This invention relates especially to tape moistening machines which can deliver series of strips of moistened gummed tape, 15 the strips in each series being of different lengths according to the particular requirements of use. In ordinary carton sealing two short and one long strip are usually desirable and the machine may be adjusted to 20 deliver any desired number of such series of different length strips in moistened condition so as to be ready for sealing purposes. If desired, the cutter devices severing the strips may be positively geared from the feed 25 or delivery devices so as to more accurately sever the strips and insure their having the lengths desired.

In the accompanying drawing showing in a somewhat diagrammatic way illustrative 30 embodiments of this invention,

Figure 1 is a side elevation, partly in section.

Fig. 2 is a longitudinal vertical section taken substantially along the line 2—2 of 35 Fig. 3.

Fig. 3 is a top view, parts being removed for greater clearness.

Fig. 4 is a detail of the cut-off cam devices.

Fig. 5 shows the moistener and presser mechanism.

Fig. 6 is a transverse sectional view of the cut-off cam; and

Fig. 7 is a detail showing the preferred 45 presser roll construction.

The machine may be provided with a rigid frame 1 of any suitable construction on which may be mounted the electric or other motor 2, so that the motor clutch member 3 50 may be moved from its inoperative position indicated in such way as, to couple the worm shaft 10 to the motor. This may be effected by the pivoted arm 4 swinging about the pin 5 and normally held in inoperative position by the spring 156. The rod 6 may be

connected to this arm and to the treadle operating member or treadle lever 7 adapted to be moved by the operator in any suitable way as through the link 8 and treadle 9, which may be arranged adjacent the floor 60 and preferably near the delivery end of the machine so as to be convenient for the operator receiving and applying the gummed strips. For example, the operator may stand on this treadle so long as he desires to have the machine deliver gummed sealing strips, or the treadle or clutch operating device may be arranged with sufficient stiffness or frictional holding power so as to remain in either the clutched or unclutched position. 65 The operating parts of the machine may be connected to the motor in any suitable way as through the worm 11 on the worm shaft 10 meshing with the worm wheel 12 on the drive shaft 13 which may extend transversely across the machine. This drive shaft may as indicated in Fig. 2 carry the gear 40 which may drive the feed rolls 44, 45 through suitable intermediate gearing, such as the spur gears 41, 42 43 and 46, which 70 may thus positively drive the feed rolls at the desired linear speed so as to correspondingly withdraw the strip of gummed cloth or paper tape 114 from the tape roll 115 mounted in any suitable way. If desired, 75 the tape may pass over the guide rolls 124 and 125, and also in some cases the coöperating tension rolls 123 may be interposed to promote proper tensioning, straightening and feeding, these tension rolls being, if desired, mounted in the yoke 122 guided in 80 suitable vertical guides in the side members of the frame as shown in Fig. 1. For some purposes it is desirable to have the feed rolls disengageable so that their feeding engagement on the tape may be stopped when desired and this may be conveniently effected by mounting, as indicated in Fig. 3, the upper feed roll 45 in suitable slides 47 which 85 may be vertically movable in the slide ways 90 or guides 49. These slides may have pins 48 projecting therefrom so as to be engaged by the arms 50 on the lifting lever 51 having the handle 52 extending therefrom as indicated. 95 From the feed rolls 44, 45 the gummed tape may pass between suitable guides, such as 39, as diagrammatically indicated in Fig. 2, to suitable cutter rolls 37, 38 intermittently operated through any suitable mecha- 100 105 110

nism, such as will be subsequently described so as to sever the gummed tape into strips of the desired lengths to form the series of different strips desired. From the cutter 5 rolls the strips may pass through suitable guides which, of course, preferably engage the cutter rolls more closely than is diagrammatically indicated in Fig. 2 and which effectively guide the tape to the delivery devices or belts 62, 63. These delivery 10 belts which may, as indicated in Fig. 3, be formed of separate belts or strips of felt, cloth or other suitable material, may be positively driven through any suitable mechanism 15 preferably at a linear speed slightly in excess of the feed rolls so as to keep the tape taut and promote severance of the strips. The lower feed belts 62 may as indicated be supported on a suitable plate 162 and be 20 mounted on suitable rolls 61, 70, at any desired distance apart and driven at the desired speed as from the gear 40 through the intermediate gears 53, 54, and the gear 55 on the roll 61. If desired, also the coöperating 25 forward roll on which these delivery belts 62 are mounted may be positively driven, and for this purpose the shaft 56 of the roll 61 may have arranged thereon a suitable sprocket wheel 57, as indicated in Fig. 30 3, so as to operate the drive chain 58 engaging a sprocket wheel 69 on the shaft 73 of the forward belt roll in connection, if desired, with the tightener sprocket 120 on the movable arm 121. In this way the lower 35 belts are positively driven at the desired speed and the upper delivery belts 63 may also be positively driven as by mounting these belts on the rolls 60, 66, which are geared to the other belt rolls below. The 40 gear 59 on the belt roll 60 may, for instance, mesh with the gear 55 on the belt roll 61 and the gear 67 on the belt roll 66 at the delivery end of these belts may mesh with the gear 68 on the belt roll 70 below. For purposes 45 of inspection, and so forth, it is desirable to have the upper delivery belts removably mounted in the machine and this may be conveniently effected by mounting them on a removable frame comprising the 50 side plates 64 in which the belt rolls are mounted, and these side plates may have the projecting pins 65 loosely fitting within vertical slots 165 in the frame of the machine at one or both ends of the belts so as 55 to hold the frame and upper belts in proper position, while at the same time allowing them to be vertically lifted at one or both ends and also promoting by the weight of the parts their proper engagement with the 60 delivery belts below.

The tape strips issuing from the forward delivery belt rolls may be received between any suitable stationary guides, such as 117, and may then pass through the moistener 65 device of any desired character, such, for

example, as the moistener roll 91 and co-operating presser roll 118 shown in Fig. 2 to effectively moisten the gummed tape strips 114 which thus are delivered in such condition as to be applied to cartons or other packages or articles to be sealed or for other uses. The moistener roll 91, which is preferably driven at two or three times the surface speed of the delivery belts so as to suitably space apart the delivered strips 75 may be mounted on the shaft 90 revolvably supported in the frame of the machine so that the roll normally dips into the water tank 92 which may be supported on the machine frame as by resting on the block or 80 member 127 and on the removable tank support 126 which firmly supports the water tank when in raised position indicated, while it may, of course, be swung forward and downward so as to allow the water tank 85 to be withdrawn from the machine for refilling or for cleaning the moistener or other purposes. The moistener roll may, if desired, be provided with suitable longitudinal slots or fine corrugations 116 adapted to 90 carry the water up the roll in regulated quantities and it is sometimes desirable to have separated annular recesses, such as 113, formed in this roll as shown in Fig. 3, so that guides 173 or forwardly projecting tips 95 of the disengaging guides or fingers on the guide member 101 may fit within these recesses and prevent the gummed tape from being carried around in contact with the moistener roll. This guide member 101 may 100 as indicated in Fig. 5 be mounted on the pin or pawl 100 and be normally lightly pressed downward as by a spring 98, while the adjusting screws 102 on one or both sides of this member may be arranged to engage with the stationary pins 103 so as to accurately regulate the position of this guide member. It is also desirable to have a scraper or doctor 95 arranged in coöperation with the moistener roll on its rising side 110 so as to regulate the amount of moisture carried up thereby, which, if desired, may be such as to practically fill the longitudinal corrugations or slots 116. This doctor 95 may, if desired, be mounted on the doctor 115 levers 94 pivoted to the pin or bar 93 and normally pressed inward as by the spring 96. The coöperating presser roll 118 is preferably positively driven in unison with the moistener roll 91, or, if desired, at a slightly 120 greater surface speed through suitable gearing, such as 88, 130 shown in Fig. 3, and the moistener and presser roll may be advantageously geared to the other moving parts of the machine. This may be accomplished, as shown in Figs. 1 and 2, by the pinion 87 on the moistener roll shaft 90 which may mesh with the spur wheel 86 on the stud shaft 89 so as to be driven by the gear 68 on the shaft 73 driven as previously 130

described. It is also desirable that this presser roll should be accurately positioned with respect to the moistener. For this purpose the presser roll shaft 119 may be 5 mounted in the presser arms 106 pivoted about the pins 112 and normally forcing the presser roll downward as by suitable springs 111. Adjusting screws, such as 107 may be arranged in these presser arms so as to co- 10 operate with the stationary stops or abutments 108 and positively regulate the positioning of this presser roll which may thus be yieldingly held at a distance of a few thousandths of an inch from the moistening 15 roll below when no gummed tape is passing between these rolls. Then when a gummed strip is carried forward by the delivery belts the presser roll rises slightly so as to allow the strip to pass beneath it, while at 20 the same time the strip is pressed down into reliable moistening contact with the moistening roll below so as to uniformly and thoroughly moisten its gummed surface. It is desirable to minimize the amount of 25 moisture received by the presser roll when the gummed tape is not passing thereunder, and for this purpose the presser roll may be advantageously formed of suitable water repellent material besides having such 30 water as may be delivered thereto removed therefrom before that part of the presser roll comes down again opposite to the moistener. The presser roll may, for example, be formed of wax impregnated disks of paper, 35 a series of such disks being shown in Fig. 7 as compressed between suitable end cheeks or plates 140. If paper is thoroughly impregnated or saturated with paraffin or other suitable wax and compressed in this 40 way, the resulting built-up roll may be turned down and smoothed or otherwise shaped into cylindrical form so as to have a substantially uniform durable surface of a water repellent character which receives 45 a minimum amount of water from the moistener roll below. If desired, also, any water that is transferred to this presser roll may be removed therefrom as by a suitable scraper 109 which may coöperate with the 50 rearward descending side of the presser roll to remove this water and guide the same out laterally to the sides where it can drip from the ends of the trough-like scraper down again into the water tank 92. This scraper 55 may, as indicated, be supported by suitable brackets 110 secured to the presser arms 106.

The cutter is preferably operated by suitable change or variable speed gearing so as 60 to positively and reliably actuate the cutter at the desired intervals to sever any desired number of series of different length strips having the lengths required for the particular service. This may be done, in any suitable way as for example, by actuating the

75 cutter mechanism from the gear 75 on the shaft 72 which as indicated in Fig. 3 carries at its other end gear 71 which may mesh with the gear 68 on shaft 73. A suitable change gear sector 81 may coöperate with 80 the shaft 72 and be adjusted in desired position as by the wing nut 84 coöperating with the sector slot 83 in this member. The radial gear slot 82 may thus be adjusted in angular position so as to hold in proper position a pair of connected change gears, such as 76, meshing with the gear 75, and 77 meshing with the gear 78 on shaft 28. It is of course understood that these change gears may be removed and replaced by 85 others by removing the nut 79 on the sliding stud shaft 80 of well known construction. In this way the cut-off or cam shaft 28 may be driven at any desired speed as compared with the other elements of the machine and 90 the cut-off cam 29 on this shaft 28 may thus be rotated through one revolution every time the tape feeding and delivering devices deliver a length of tape corresponding to the aggregate length of the different strips making up a complete series. This change gearing thus regulates the total or aggregate length of the strips in a series and the arrangement of the operating members or recesses 30 on the cut-off cam determines the 95 relative lengths of the different strips in any one series, since every time one of these operating cam members moves into engagement with the projecting finger 27 as shown in Figs. 4 and 6, a strip of gummed tape is 100 severed through appropriate connections. As indicated in Fig. 6 these operating cam members 30 are so spaced around the cam 29 as to give relative lengths of 2 to 1 to 1 in the three strips forming a series, although 105 it is, of course, understood that this cam may be replaced by another having a different number or relative positioning of these operating cam members so as to vary the number or relative length of the different strips in a series. Any suitable connections may be used to operate the cutter devices from the cut-off cam, and if desired, the cut-off or clutch lever 26 having the projection 110 or finger 27 engaging the cam recesses 30 may be mounted on the rock shaft or clutch rod 24, as shown in Figs. 4 and 1, and the clutch detent 21 on the other end of this clutch rod which may be supported in suitable brackets or bearings 23, 25 may coöperate with the pin 20 of a one-revolution stop motion clutch of any suitable construction. As indicated, the clutch dog 19 is normally 115 spring-pressed outward into engagement with the teeth 16 of the clutch wheel 15 so as to couple the cutter shaft 17 to this continuously revolving clutch wheel so long as the clutch detent is swung out of the path of the pin. As shown in Figs. 1 and 3 this clutch dog 19 may be slidingly mounted in a 120 125 130

suitable clutch arm 18 having its sleeve 153 secured as by the pin 34 to the clutch shaft 17. The clutch wheel 15 may as indicated be connected by a suitable pin 154 with the 5 spur gear 14 meshing with the gear 32 on the driving shaft 13 so as to constantly rotate this clutch wheel, which is loose on the cutter shaft. The cutter shaft 17 carries the cutter roll 38 which is geared to the coöperating 10 cutter roll 37 by gears 35, 36, as shown in Fig. 2. In this way whenever the cut-off cam actuates the clutch detent and withdraws it from the clutch pin 20 this instantly starts the revolution of these cutter rolls so as to 15 promptly bring them into cutting engagement with the gummed strip and then after these cutter rolls have made a single revolution the clutch detent has been restored to its stopping position in the path of the pin 20 which is thus wedged radially inward 20 into its inoperative position out of contact with the clutch wheel, so that the cutter rolls are normally held in the inactive position shown in Fig. 2, allowing the gummed tape 25 to pass freely between them.

It is thus apparent that the gummed tape so long as the clutch treadle is held down by the operator's foot or by suitable latch mechanism so that the drive shaft is rotated, and 30 so long as the lifting lever 52 is not operated to disengage the feed rolls the gummed tape is continuously fed forward by the feed rolls. Then at the proper intervals the gummed 35 tape is severed into strips of the desired relative lengths to form the series required and these severed strips are taken by the delivery belts and are then engaged and fed forward more rapidly and thus separated while they are being moistened by the moistener mechanism, and are finally delivered 40 at the end of the machine to be conveniently grasped and used by the operator. The adjustable cut-off change gearing described makes it possible to accurately adjust the absolute length of the strips forming 45 a series, so that, for example, the strips may be within a sixteenth of an inch or so of the standard lengths, and if a different multiple length series of strips is to be delivered by the machine another cut-off cam 50 may be substituted thereon having the cam operating members or devices so positioned as to give two, three, four or more different properly proportioned length strips in each 55 series.

This invention has been described in connection with a number of illustrative embodiments, forms, proportions, materials, sizes, arrangements, and methods of use, to 60 the details of which disclosure the invention is not, of course, to be limited, since what is claimed as new and what is desired to be covered by Letters Patent is set forth in the appended claims.

65 1. In tape moistening machines, feed rolls

to engage and feed forward a strip of gummed tape, cutter devices to intermittently engage and sever the tape into lengths, delivery belts to receive and carry forward the severed strips and moving at a 70 slightly greater surface speed than said feed rolls and tape moistening devices coöperating with the discharge end of said delivery belts and operating at several times the surface speed of said belts to moisten the severed strips and cutter actuating devices comprising a one revolution stop motion clutch and a connected cut-off cam positively 75 geared to the feeding or delivering elements of the machine and having a series of spaced cam operating members arranged at different spaced intervals around the cam to periodically actuate said cutter devices and sever the tape into recurring series each comprising strips of different lengths. 80

2. In tape moistening machines, feed rolls to engage and feed forward a strip of gummed tape, cutter devices to intermittently engage and sever the tape into lengths, delivery belts to receive and carry 90 forward the severed strips and tape moistening devices coöperating with the discharge end of said delivery belts and operating at several times the surface speed of said belts to moisten the severed strips and cutter actuating devices comprising a one revolution stop motion clutch and a connected cut-off cam having a series of spaced cam operating members arranged at different spaced intervals around the cam to periodically actuate 95 said cutter devices and sever the tape into recurring series each comprising strips of different lengths. 100

3. In tape moistening machines, feed rolls to engage and feed forward a strip of 105 gummed tape, cutter devices to intermittently engage and sever the tape into lengths, delivery belts to receive and carry forward the severed strips and tape moistening devices to moisten the severed strips and cutter actuating devices comprising a connected cut-off cam having a series of spaced cam operating members arranged at different spaced intervals around the cam to periodically actuate 110 said cutter devices and sever the tape into recurring series each comprising strips of different lengths. 115

4. In tape moistening machines, cutter devices to engage and sever gummed tape into lengths, delivery belts to receive and 120 carry forward the severed strips and tape moistening devices coöperating with the discharge end of said delivery belts and operating at greater surface speed than that of said belts to moisten the severed strips and 125 cutter actuating devices comprising a one revolution stop motion clutch and a connected cut-off cam having a series of spaced cam operating members arranged at different spaced intervals around the cam to 130

periodically actuate said cutter devices and sever the tape into recurring series each comprising strips of different lengths.

5. In tape moistening machines, cutter devices to engage and sever gummed tape into lengths, and tape moistening devices to moisten the severed strips and cutter actuating devices comprising a one revolution stop motion clutch and a connected cut-off 10 cam having a series of spaced cam operating members arranged at different spaced intervals around the cam to periodically actuate said cutter devices and sever the tape into recurring series each comprising 15 strips of different lengths.

6. In tape moistening machines, feed means to engage and feed forward a strip of gummed tape, cutter devices to engage and sever the tape transversely into recurring 20 ring series each comprising strips of different lengths, delivery belts to receive and carry forward the severed strips and tape moistening devices coöperating with the discharge end of said delivery belts to moisten 25 the severed strips and comprising a moistener roll having recesses to carry water to the tape and a coöperating presser roll to engage tape and yieldingly force it into moistening contact with the moistener roll, said 30 presser roll having a water repellent peripheral surface, means to positively rotate said moistener roll and means to positively rotate said presser roll at a linear speed slightly greater than that of the moistener 35 roll, adjusting devices to regulate the minimum distance between said moistener and presser rolls to less than the thickness of the gummed tape passing between them and allow the yielding separation of said rolls 40 as the tape engages them.

7. In tape moistening machines, feed means to engage and feed forward a strip of gummed tape, cutter devices to engage and sever the tape transversely into recurring 45 ring series each comprising strips of different lengths, delivery belts to receive and carry forward the severed strips and tape moistening devices coöperating with the discharge end of said delivery belts to moisten 50 the severed strips and comprising a moistener roll having recesses to carry water to the tape and a coöperating presser roll to engage tape and yieldingly force it into moistening contact with the moistener roll, 55 means to positively rotate said moistener roll and means to positively rotate said presser roll at a linear speed slightly greater than that of the moistener roll, adjusting devices to regulate the minimum distance 60 between said moistener and presser rolls to less than the thickness of the gummed tape passing between them and allow the yielding separation of said rolls as the tape engages them.

8. In tape moistening machines, feed

means to engage and feed forward a strip of gummed tape, cutter devices to engage and sever the tape transversely into recurring series each comprising strips of different lengths, delivery belts to receive and carry forward the severed strips and tape moistening devices coöperating with the discharge end of said delivery belts to moisten the severed strips and comprising a moistener roll and a coöperating presser roll to engage tape and yieldingly force it into moistening contact with the moistener roll.

9. In tape moistening machines, feed rolls to engage and feed forward a strip of gummed tape, cutter devices to engage and sever the tape into lengths, delivery belts to receive and carry forward the severed strips and moving at a slightly greater surface speed than said feed rolls and tape moistening devices coöperating with the discharge end of said delivery belts to moisten the severed strips and cutter actuating devices comprising a cut-off cam positively geared to a tape feeding element of the machine and having a series of spaced cam operating members arranged at different spaced intervals around the cam to periodically actuate said cutter devices and sever the tape into recurring series each comprising 90 strips of different lengths. 95

10. In tape moistening machines, feed rolls to engage and feed forward a strip of gummed tape, cutter devices to engage and sever the tape into lengths, delivery belts to receive and carry forward the severed strips and tape moistening devices coöperating with the discharge end of said delivery belts to moisten the severed strips and cutter actuating devices to periodically actuate said cutter devices and sever the tape into recurring series each comprising strips of different lengths. 100 105

11. In tape moistening machines, mechanism to engage and feed forward a strip of gummed tape, cutter devices to engage and sever the tape transversely into recurring series each comprising strips of different length, feed devices to receive and yieldingly carry forward the severed strips and tape moistening discharging devices coöperating with the discharge end of said delivery devices to moisten the severed strips and feed them forward at a faster rate to separate the different strips. 110 115

12. In tape moistening machines, means to feed gummed tape, cutter devices to sever the tape into lengths, tape moistening devices to moisten the severed strips and cutter actuating means comprising an interchangeable cam positively gear connected to an operating feeding element of the machine and having a series of spaced cam operating members arranged at different spaced intervals around the cam to actuate said cutter device and sever the tape into 120 125 130

- 6
- recurring series, each comprising strips of different predetermined lengths.
13. In tape moistening machines, means to feed gummed tape, cutter devices to sever the tape into lengths, tape moistening devices to moisten the severed strips and cutter actuating means comprising a cam positively connected to an operating feeding element of the machine and having a series of spaced cam operating members arranged at different spaced intervals around the cam to actuate said cutter device and sever the tape into recurring series, each comprising strips of different predetermined lengths.
14. In tape moistening machines, means to feed gummed tape, cutter devices to sever the tape into recurring series, each comprising strips of different predetermined proportionate lengths, means to adjust the aggregate length of the strips in each series and tape moistening devices to moisten the severed strips.
15. In tape moistening machines, means to feed gummed tape, cutter devices to automatically sever the tape into recurring series, each comprising strips of different predetermined lengths, and tape moistening devices to moisten the severed strips.
16. In tape moistening machines, tape feeding means, cutter devices to intermittently sever the tape into lengths, moistening means and cutter actuating means comprising an interchangeable cam connected to said tape feeding means having a series of spaced cam operating members arranged at different spaced intervals around the cam to periodically actuate said cutter device and sever the tape into recurring series, each comprising strips of different predetermined proportionate lengths.
17. In tape moistening machines, cutter devices to intermittently sever the tape into lengths, moistening means and cutter actuating means comprising a cam connected to said tape feeding means having a series of spaced cam operating members arranged at different spaced intervals around the cam to periodically actuate said cutter device and sever the tape into recurring series, each comprising strips of different predetermined lengths.
18. In tape moistening machines, moistening means and cutter devices to sever the tape into recurring series, each comprising strips of different predetermined lengths.
19. In tape moistening machines, means to feed and sever a strip of gummed tape into lengths and moistening means for the severed lengths of tape comprising a moistener roll having longitudinal water carrying corrugations and recesses to carry water to the tape and a coöperating presser roll above said moistener roll to engage the tape and yieldingly force it into moistening contact with the moistener roll, said presser roll
- having a water repellent peripheral surface formed by the exposed edges of compressed disks of paraffined paper, means to positively rotate said moistener roll and means to positively rotate said presser roll at a linear speed slightly greater than that of the moistener roll, adjusting devices to regulate the minimum distance between said moistener and presser rolls to less than the thickness of the gummed tape passing between them and allow the yielding separation of said rolls as the tape engages them and a scraper coöperating with said presser roll to remove adherent water therefrom.
20. In tape moistening machines, means to feed and sever a strip of gummed tape into lengths and moistening means for the severed lengths of tape comprising a moistener roll to carry water to the tape and a coöperating presser roll above said moistener roll to engage the tape and yieldingly force it into moistening contact with the moistener roll, said presser roll having a water repellent peripheral surface formed by the exposed edges of compressed disks of paraffined paper, means to positively rotate said moistener roll and means to positively rotate said presser roll, adjusting devices to regulate the minimum distance between said moistener and presser rolls to less than the thickness of the gummed tape passing between them and a scraper coöperating with said presser roll to remove adherent water therefrom.
21. In tape moistening machines, means to feed and sever a strip of gummed tape and moistening means for the tape comprising a moistener roll to carry water to the tape and a coöperating presser roll above said moistener roll to engage the tape and yieldingly force it into moistening contact with the moistener roll, said presser roll having a water repellent peripheral surface, means to positively rotate said moistener roll and means to positively rotate said presser roll, adjusting devices to regulate the minimum distance between said moistener and presser rolls to less than the thickness of the gummed tape passing between them and a scraper coöperating with said presser roll to remove adherent water therefrom.
22. In tape moistening machines, means to feed and sever gummed tape into lengths and coöperating moistening means for the severed lengths of tape comprising a moistener roll having water carrying depressions to carry liquid to the tape and a coöperating presser roll above said moistener roll to engage the tape and yieldingly force it into moistening contact with the moistener roll, said presser roll having a water repellent peripheral surface formed of compressed disks of paraffined paper, means to positively rotate said moistener roll and means to rotate said presser roll at a linear speed

slightly greater than that of the moistener roll and a scraper coöperating with said presser roll to remove adherent water therefrom.

23. In tape moistening machines, means to feed and sever gummed tape and coöperating moistening means comprising a moistener roll having water carrying depressions to carry liquid to the tape and a coöperating presser roll above said moistener roll to engage the tape and yieldingly force it into moistening contact with the moistener roll, said presser roll having a water repellent peripheral surface and means to rotate said presser roll at a linear speed slightly greater than that of the moistener roll.

24. In tape moistening machines, means to feed and sever gummed tape and coöperating moistening means comprising a moistener roll and a coöperating presser roll above said moistener roll to engage the tape and yieldingly force it into moistening contact with the moistener roll, and adjusting

devices to regulate the minimum distance 25 between said moistener and presser rolls to less than the thickness of the gummed tape passing between them and allow the yielding separation of said rolls as the tape engages them.

25. In tape moistening machines, means to supply gummed tape and means to automatically sever from said supply recurring series each comprising strips of different predetermined lengths and moisten and deliver the same successively.

26. In tape moistening machines, feed devices and coöperating cutter and moistening devices to automatically sever, moisten and deliver recurring series of strips of gummed 40 tape, each series comprising successively delivered strips of different predetermined relative length.

CHARLES H. CROWELL.
